RECEPTACLE CLOSURE LOCK

Walter L. Vinson, Sherman Oaks, Calif.

Application November 23, 1946, Serial No. 711,949

10 Claims. (Cl. 220—58)

1

This invention relates to improvements in receptacles which are provided with pivoted bails and flanged closures or lids, such as garbage cans, pails and similar containers and has for an object the provision of a novel and efficient means for locking the closure or lid in place when the bail of the receptacle is swung downwardly into its inoperative position and for releasing lid or closure when the bail is swung upwardly, thereby preventing dogs and other animals from removing the lid and assuring that the lid will remain tightly in place to prevent the escape of disagreeable garbage odors.

Another object of the present invention is to provide a simply constructed locking means of the character described which is reliable in operation, comparatively small and compact and affords the advantages herein set forth by reason of the particular construction, interrelation and operation, of a pair of rotary cam members and spring loaded latch hooks, to which cam members the ends of the bail are fixed so that responsive to the swinging of the bail, said latch hooks will move into and out of position for locking the closure in place.

Another object is to provide a locking means such as described which will operate to tighten and seal the lid or closure as well as securely hold it against accidental removal, thereby preventing the escape of disagreeable odors and the attraction of insects.

Another object is to provide an improved construction in garbage pails and the like whereby the pail is effectively reinforced and made more durable and reliable in use by reason of embodying therein the particular closure lock hereof and the parts and elements associated therewith.

With the foregoing objects in view, together with such other objects and advantages as may subsequently appear, the invention resides in the parts and in the combination, construction and arrangement of parts hereinafter described and claimed, and illustrated by way of example in the accompanying drawing, in which:

Fig. 1 is a perspective view of a garbage can embodying the present invention and showing in dotted lines how the closure may be raised and removed when the bail is raised,

Fig. 2 is an enlarged fragmentary vertical sectional view of locking means embodying the present invention as when locked,

Fig. 3 is a fragmentary vertical sectional view taken on the line 3—3 of Fig. 2,

Fig. 4 is a sectional view similar to Fig. 2 with the locking means in unlocked position and

2

Fig. 5 is perspective view of one of the cam members.

As shown in the accompanying drawing the present invention is embodied in a garbage can A, having a flanged cover or lid B and provided with a pivoted bail C. A band 5 is pressed on or otherwise mounted on the top of the can and is provided with an annular flange 6 on which a rubber or similar gasket 7 is fixed to act as a stop and seal for a reinforced bead 8 on the flange 9 of the lid. This flanged band serves also as an effective reinforcing for the can.

The locking means hereof is provided on opposite sides of the can and has the bail C connected therewith so that when the bail is moved into down position along side the can, the lid will be locked but will be released on lifting the bail part way, for example, somewhat above a horizontal position as shown in dotted lines in Fig. 1. The arrangement is such that while the bail is disposed on either side of the can between its initial released position and its upright or vertical position, the lid will be unlocked and free to be removed but will be locked against removal while the bail is between said releasing positions and its down position. Moreover the locking means is constructed and arranged so that during the movement of the bail into said down position the lid is forced downwardly against the gasket 7 and thus tightly sealed to prevent escape of objectionable odors and the attraction of insects.

The locking means on each side of the can A includes a spring-loaded latch hook 10 adapted to be moved into and out of locking contact with the bead 8 of the cover 9 responsive to the turning of an eccentrically mounted cam member 11 mounted on the can. The ends of the bail C are welded or otherwise secured to the cam members 11 so that the latter will be turned responsive to lifting and lowering of the bail.

Each cam member 11 comprises a circular body 13 having an annular flange 14 adapted to bear against the shank 10' of the hook 10. A bolt 15 is passed through the adjacent side of the can and the body 13 to one side of the center of said body and serves as a pivot for the cam member, the outer end of the bolt being riveted to hold the cam member in place.

A channel shaped guide bracket 17 is held against the side of the can on the bolt 15 by means of a riveted portion 18 whereby the shank 10' will be held in upright position and guided during movement thereof incident to moving the hook into and out of locking position. The outer

edges of the bracket 17 abut the cam member 13 to prevent wobbling thereof.

A bowed leaf spring 19 is mounted on the bolt 15 and guided by the bracket 17 between the shank 10' and the side of the can so that it will urge shank and hook into unlocking position as shown in Fig. 4. In this connection it should be noted that as the shank 10' is adapted to be moved vertically as well as axially of the bolt 15 it is provided with a longitudinal slot 19' through which the bolt extends.

The flange 14 of each cam member is provided on its margin with like locking cam surfaces 20 and 21 spaced apart less than 90 degrees and having a locking dwell surface 22 therebetween. The remainder of the margin of the flange 14 serves as an unlocking cam surface 23. That portion of the shank 10' which extends between the flange 14 and the side of the can is inwardly offset and at points opposite said flange is formed with curved or convex bearing portions 24 for contact with the cam surfaces on the margin of said flange. These portions 24 together with said cam surfaces on the margin of the flange 14, in coaction with the spring 19, provide for inward and outward movements of the latch hook 10 responsive to lowering and lifting of the bail C, the inward movement disposing the hook in locking position and the outward movement disposing the hook in unlocking position.

Means are provided to raise and lower the latch hook 10 on each side of the can so that in case the lid B is not pushed all the way down on the can the latch hooks will be positively moved into locking position with respect to the bead 8 of the lid and will force the lid down into proper position on the can. In each locking means this vertical movement is effected by the eccentric movement of the cam member 13 and the contacting of the outer peripheral surface of the flange 14 with a shoulder 26 and a lateral foot portion 27 on the shank 10'. The shoulder 26 rides on top of the flange 14 whereas the foot 27 being the outwardly bent lower end of the shank, rides against the lower side of the flange.

The cam members 13 and associated parts are arranged so that when the bail C is held up in the dotted position shown on Fig. 1 or above such position the parts of the locking means on each side of the can will be in unlocked position substantially as shown in Fig. 4. At this time the unlocking dwells 23 are in contact with the uppermost curved surfaces 24 on the shanks and the hook 10 is held outwardly by the spring 19, while the locking dwells 22 bear against the curved surfaces 24 on the lower ends of the shanks and hold the lower ends of the shanks in toward the side of the can. At this time the hooks 10 are held in their uppermost position by the eccentric cam members which have the greater portions thereof disposed above the bolt 15. The lid 9 may now be placed on the can so that the bead 8 lies below the hook 10 as shown in Fig. 4. Should, however, the lid be put on so that it is not all the way down against the gasket 7 on the lid flange 6, it will be urged against said gasket and tightly sealed during the locking operation.

After the lid is placed on the can the operator pushes the bail C down on either side of the can and in so doing turns the cam members 13 correspondingly so that they will move the hooks 10 downwardly and inwardly over and against the bead 8 and thus locks the lid in place. The downward movement of the hooks 10 is effected

by means of the flange 14 of the eccentrically mounted cam members 13 turning against the foot portions 27 on the lower ends of the shanks of said hooks whereas the inward movement is effected by corresponding cam surfaces 20 or 21 depending on which side of the can the bail is swung downwardly, the effective ones of said surfaces contacting the uppermost curved surfaces 24 on the shanks of the hooks and the dwell 22 holding the hooks in over-the-bead position. The flanges 14 are provided with like flat portions 28, certain of which are contacted by the portions 27 on the shanks of the hooks to hold the hooks against accidental movement out of locked position as shown in Figs. 2 and 3 when the bail is swung downward on one side of the can and the other of which flat portions function similarly when the bail is swung down on the other side of the can.

It will now be apparent that I have provided a simply constructed, small and compact locking means which may be inexpensively produced and readily embodied in various type of lidded receptacles wherein it is desirable to lock the lid against removal except when the bail is used to lift the receptacle. Used in garbage cans my improved means will strengthen the can and add to its life while preventing animals from knocking the lid off and will make for increased sanitation by means of a tight seal of the lid.

While I have shown and described a specific embodiment of my invention, I do not limit myself to the exact details of construction set forth, and the invention embraces such changes, modifications and equivalents of the parts and their formation and arrangement as come within the purview of the appended claims.

I claim:

1. The combination with a receptacle having a flanged closure, therefor, a bead on the lower edge of the flange of the closure, a flange on the receptacle as a seat for the beaded edge of the closure flange; of a pair of brackets fixed to opposite sides of the receptacle, cup-shaped cam members encompassing said brackets, pivots on which said cam members are mounted to turn, a bail fixed to said cam members so that said cam members will turn when the bail is raised and lowered, latch hooks having shanks slidably and vertically adjustably supported on said pivots within said brackets, spring means for forcing said hooks outwardly on said pivots, said cam members including circular body portions through which said pivots extend and to which the ends of the bail are fixed, annular flanges on said bodies facing the sides of the receptacle, and cam surfaces arranged on the annular flanges of said cam members for contacting said shanks of said hooks and moving the hooks against the action of said spring means into locking engagement with the bead on said closure incident to lowering the bail to either side of the cam and for releasing said hooks when the bail is raised.

2. The combination with a receptacle having a flanged closure, of a pair of brackets fixed to opposite sides of the receptacle, cup-shaped cam members encompassing said brackets, pivots on which said cam members are mounted to turn, a bail fixed to said cam members so as to turn the cam members when the bail is raised and lowered, latch hooks having shanks slidably and vertically adjustably supported on said pivots and guided by means of said brackets, spring means forcing said hooks outwardly on said

pivots into unlatching position, said cam members including body portions through which said pivots extend and to which the ends of the bail are fixed, flanges on said body portions facing the sides of the receptacle, and cam surfaces arranged on said flanges of said cam members for contacting said shanks of said hooks and moving the hooks against the action of said spring means into locking engagement with said closure incident to lowering of the bail to either side of the cam and for releasing said hooks when the bail is raised, said body portions contacting the outer edges of said brackets.

3. The combination with a receptacle having a flanged closure and a flange on the receptacle as a seat for the closure flange, of a pair of brackets fixed to opposite sides of the receptacle, cam members encompassing said brackets, pivots on said receptacle on which said cam members are eccentrically mounted, a bail fixed to said cam members so as to turn the latter when raised and lowered, latch hooks having shanks laterally and vertically adjustably supported on said pivots within said brackets, spring means for forcing said shanks outwardly on said pivots, said cam members including circular bodies through which said pivots extend and to which the ends of the bail are fixed, and annular flanges on said bodies, cam surfaces arranged on the annular flanges of said cam members for contacting said shanks of said hooks and moving the hooks inwardly against said spring means into locking engagement with the flange on said closure incident to lowering of the bail to either side of the receptacle and for releasing said hooks when the bail is raised, lateral projections on said shanks, the flanges of said cam members being arranged to contact said projections and pull downwardly on said hooks to tighten the closure when the hooks are moved into locking position, also operating against said projections to raise the hooks when the bail is lifted upwardly.

4. The combination with a receptacle having a pivoted bail and a removable closure of a locking means for releasably locking the closure, on the receptacle including a cam member rotatably mounted on the receptacle and connected with the bail so as to turn when the bail is swung upwardly and downwardly, a latch hook, means mounted on the receptacle for supporting and guiding said latch hook for movement into and out of locking contact with said closure, and coacting cam elements on the cam member and said latch hook respectively, constructed and arranged to move the latch hook into closure-locking position when the bail is lowered and to release said hook when the bail is raised.

5. The combination with a receptacle having a pivoted bail and a removable closure, of a locking means for releasably locking the closure on the receptacle including a cam member rotatably mounted on the receptacle and connected with the bail so as to turn when the bail is swung upwardly and downwardly, a latch hook, means mounted on the receptacle for supporting and guiding said latch hook for movement into and out of locking contact with said closure, and means responding to the turning of said cam member for moving said hook into and out of position for locking the closure on the receptacle including coacting cam portions on said cam members and said hook respectively.

6. The combination with a receptacle having a removable closure, a rotary cam member, means for mounting said cam member on a side of the

receptacle, a pivoted bail for said receptacle connected with said cam member so as to turn the cam member on raising and lowering of the bail, of a latch hook mounted between said cam member and said side of the receptacle for movement relative thereto into and out of position to lock the closure on the receptacle, and coacting cam portions on said hook and said cam member for moving said latch hook into and out of position to lock the closure in place when the bail is lowered and raised respectively.

7. The combination with a receptacle having a removable closure, of a rotary cam member, means for mounting said cam member on a side of the receptacle, a pivoted bail for said receptacle connected with said cam member so as to turn the cam member on raising and lowering of the bail, a latch hook mounted between said cam member and said side of the receptacle for movement relative thereto into and out of position to lock the closure on the receptacle and coacting cam portions on said hook and said cam member for moving said latch hook into and out of position to lock the closure in place when the bail is lowered and raised respectively and other coacting cam portions on said hook and said cam member respectively for moving said hook vertically during the turning of said cam member.

8. The combination with a receptacle having a closure, of cup-shaped rotary cam members, means for mounting said cam members on the opposite sides of the receptacle, a bail fixed to said cam members so that the cam members will turn when the bail is raised and lowered, latch hooks having shanks slidably and vertically adjustably supported between the cam members and said sides of the receptacle on the mounting means for said cam members so that said hooks may be moved into and out of locking contact with said closure, and coacting cam elements on said shanks and said cam members for moving said hooks into and out of locking contact with said closure.

9. The combination with a receptacle having a closure, of a pair of brackets fixed to opposite sides of the receptacle, cup-shaped cam members encompassing said brackets, pivots on which said cam members are mounted to turn, a bail fixed to said cam members so as to turn the cam members when the bail is raised and lowered, latch hooks having shanks slidably and vertically adjustably supported on said pivots and guided by means of said brackets, said cam members including body portions through which said pivots extend and to which the ends of the bail are fixed, flanges on said body portions facing the sides of the receptacle, and cam surfaces arranged on said flanges of said cam members for contacting said shanks of said hooks and moving the hooks into locking engagement with said closure incident to lowering of the bail to either side of the cam and for releasing said hooks when the bail is raised.

10. The combination with a receptacle having a closure of a pair of brackets fixed to opposite sides of the receptacle, cam members encompassing said brackets, pivots on said receptacle on which said cam members are eccentrically mounted, a bail fixed to said cam members so as to turn the latter when raised and lowered, latch hooks having shanks laterally and vertically adjustably supported on said pivots within said brackets, said cam members including circular bodies to which the ends of the bail are fixed, and annular flanges on said bodies, cam surfaces

arranged on the annular flanges of said cam members for contacting said shanks of said hooks and moving the hooks inwardly into locking engagement with the flange on said closure incident to lowering of the bail to either side of the receptacle and for releasing said hooks when the bail is raised, lateral projections on said shanks, the flanges of said cam members being arranged to contact said projections and pull downwardly on said hooks to tighten the closure when the hooks are moved into locking position,

also, operating against said projections to raise the hooks when the bail is lifted upwardly.
